UNITED STATES PATENT OFFICE

FREDERICK BEDELL, OF ITHACA, NEW YORK

ALTERNATING-CURRENT TRANSFORMER

Application filed October 18, 1928. Serial No. 313,357.

My invention relates to improvements in alternating current transformers, whereby the voltage delivered to secondary receiving devices is independent, or substantially independent, of variations in primary supply voltage. Many types of receiving devices require for best operation a more constant voltage supply than can usually be obtained from a generator or from the distribution 10 lines of a power system.

An object of my invention is to provide transformers for operating such devices at constant voltage and hence also at constant current, irrespective of variations in the voltage 15 of a supply line or generator. The secondary receiver may consist of a single device, or several devices (such as the filaments of lamps or radio tubes) arranged either in series, as in Fig. 1, or in multiple, as in 20 Fig. 2, or in series-multiple. While such devices may from time to time be changed or adjusted, if desired, the purpose of my invention is not to maintain the secondary voltage or current constant, irrespective of 25 such changes or adjustments, but after such changes or adjustments, if any, are made, to maintain constant both secondary current and secondary voltage while primary current and voltage are both varying.

30 My invention consists in the disposition of the secondary winding of the transformer with respect to the magnetic circuit and to the primary winding, so that only part of the magnetic flux set up by the primary 35 winding (hereafter referred to as the primary) passes through or links with the secondary winding (hereafter referred to as the secondary). In order to accomplish this, the secondary is displaced with respect to 40 the primary so that, on account of magnetic leakage, it is loosely coupled therewith. This is contrary to the usual practice in the construction of transformers for power and light, in which the primary and secondary 45 are placed closely together in such a way that they are closely coupled, magnetic leakage being made a minimum.

My invention consists, further, in proportioning the iron in that part of the magnetic circuit which conducts the magnetic flux

through the windings of the secondary, so that, under normal operation, such iron is at high magnetic saturation. This may be accomplished by placing the primary on one limb of the magnetic circuit and the secondary on another limb the cross-section of which is so reduced that the iron is operated, magnetically, above the knee of the saturation curve. In this case the increase in magnetizing ampere turns, resulting from an 55 increase in primary voltage and current, is accompanied by a nearly proportional increase in the reluctance of the iron, which is already saturated. A considerable increase (or decrease) in primary voltage and current 60 may thus occur with only a small increase (or decrease) in secondary flux and hence in secondary voltage and current.

My invention consists further in the provision of a leakage path for the surplus magnetic flux set up by the primary which does not pass through or link with the secondary, such leakage path being preferably in part 70 through air or other non-magnetic material, the magnetic reluctance of which is independent of saturation. As the total flux is increased, therefore, due to an increase in primary voltage and so in magnetizing ampere turns, a greater proportion of this total flux 75 passes through this leakage path; the increase 80 in the flux threading the secondary, and, hence, the increase in the secondary voltage, is, therefore relatively small.

Finally, to compensate for this relatively 85 small increase in secondary voltage, with increase in primary voltage, my invention includes a compensating winding, displaced with respect to the secondary and connected differentially therewith. The voltage of this 90 compensating winding (which is less than the secondary voltage) is thus subtracted from the voltage of the secondary. To carry out this part of my invention, the compensating winding is displaced, with reference to 95 the secondary, so as to be on a part of the magnetic circuit of lower magnetic saturation, preferably below the knee of saturation. A change in primary voltage thus makes a corresponding change in the voltage of the compensating winding, which has such a number 100

of turns (relative to the number of turns in the secondary) that, when the voltage of the compensating winding is subtracted from the voltage of the secondary, the resultant voltage delivered to the secondary is practically constant.

My invention is illustrated in the accompanying drawings forming part of this application, in which:

10 Figure 1 represents a general embodiment of my invention.

Figure 2 is a modified form thereof.

15 Figure 3 is a view of another modified form in which the compensating winding is energized by a separate transformer.

Referring now particularly to Fig. 1 I have shown therein the closed magnetic circuit of a transformer including limbs A₁ and B₁. On the limb A₁ is the primary winding P₁, 20 which is connected by the conductor p₁ to the lines leading from some source of current such as the generator G₁. The limb B₁ has the secondary winding S₁, which, as will be noted, is displaced with respect to the primary winding so as to be loosely coupled therewith, and hence to be threaded with only such part of the magnetic flux produced by the primary winding as passes through the limb B₁. In this figure the dotted line L₁ indicates a leakage path taken by the surplus magnetic flux produced by the primary winding P₁ which does not thread the secondary S₁. A compensating winding C₁ displaced 25 with reference to the secondary winding S₁ is provided, this winding being of lower voltage than S₁ and being connected differentially thereto so that its voltage is subtracted from the voltage of S₁. At R₁ I have shown receiving devices which in the present instance are 30 connected in series.

40 In Figure 2 I have shown a construction in which the limb B₂ which passes through the secondary winding S₂ is of smaller cross section and of higher magnetic saturation 45 than the limb A₂ upon which the primary P₂ is wound. The reluctance of the limb B₂ is thus increased. Furthermore the leakage path L₂ is shortened, due to the projecting parts V₂ of the magnetic circuit and the reluctance of the leakage path is thus decreased. 50 An air gap, however, is retained so that the reluctance of the leakage path is practically independent of saturation.

55 Figure 2 likewise shows a modification in which some of the turns of the primary P₂ and of the compensating winding C₂ are common. Any or all of the turns of one of these windings may be common to the other winding.

60 Although I prefer that the compensating winding forms part of the same transformer as the secondary winding, as shown in Figures 1 and 2, the compensating winding may, if desired, be derived from another separate 65 transformer, said transformer having little

magnetic leakage so that the voltage of the compensating winding varies practically in proportion to the primary voltage. Thus in Fig. 3 I have shown a transformer T₃ which is connected with the primary winding S₃. 70

I am aware that the prior art may disclose devices having paths for magnetic leakage and possibly magnetic circuits of high saturation in the secondary, for the purpose of holding either the secondary current, or the secondary voltage constant (but not both) when the load is changed, the primary current or the primary voltage being constant. The purpose of the present invention however is different. Neither the primary voltage nor the current is constant, but both the secondary voltage and current is held constant by the present invention for constant arrangement of receiving devices. 80

I claim:—

1. A transformer consisting of a magnetic circuit, a primary wound on part of said circuit with low magnetic saturation, a secondary wound on part of said circuit with a relatively high magnetic saturation, and a compensating winding comprising part of the primary winding, and being connected differentially in series with said secondary winding and with the load. 85

2. In a transformer, a magnetic circuit with varying cross-section, a primary wound on a part of said magnetic circuit with relatively large cross section, a secondary wound on part of said magnetic circuit with relatively small cross section, and a compensating winding comprising part of the primary winding and connected differentially in series with said secondary winding and with the load. 95

3. In a transformer, a magnetic circuit consisting of one portion upon which is wound a primary coil, a second portion of high magnetic saturation and variable reluctance upon which is wound a secondary coil, and a third portion containing an air gap of constant reluctance in parallel with said second portion whereby any change in the primary ampere turns causes relatively small change in the flux threading the secondary, and a compensating coil comprising part of the primary winding and connected differentially in series with said secondary winding and with the load. 105

4. In a transforming device, a magnetic circuit, a primary wound on one portion of the circuit, a secondary displaced from said primary on another portion of the circuit and a compensating winding comprising part of the primary winding and connected differentially in series with said secondary winding and with the load. 110

FREDERICK BEDELL.
